UNITED STATES PATENT OFFICE.

JAMES F. MARSTERS, OF BROOKLYN, NEW YORK.

CARTRIDGE-LOADING MECHANISM.

SPECIFICATION forming part of Letters Patent No. 284,874, dated September 11, 1883.

Application filed December 27, 1882. (No model.)

To all whom it may concern:

Be it known that I, JAMES F. MARSTERS, of Brooklyn, in Kings county, and State of New York, have invented a certain new and useful 5 Improvement in Apparatus for Filling Cartridge-Shells, of which the following is a specification.

My improvement relates to that class of apparatus which is designed for filling a number 10 of cartridge-shells at one and the same operation.

The improvement consists in combinations 15 of parts whereby this end is attained.

In the accompanying drawings, Figure 1 is 20 a plan or top view of an apparatus embodying the improvement. Fig. 2 is a central vertical section of the same. Fig. 3 is another central vertical section of the same, and Fig. 4 is a side view of a scraper which is used there- 25 with.

Similar letters of reference designate corresponding parts in all the figures.

A designates a block of wood or other suitable material provided with recesses *a*, suitable in size to contain cartridge-shells *B* to be filled, with their heads or flanges resting against the under side of the block. Of these recesses there may be any suitable number. The block is about as thick as the length of the cartridge- 30 shells to be filled.

C designates a base-piece, which may be made of wood or other suitable material, and is shown as connected by hinges *b* to the block A and extends under the same. It does not 35 fit tightly against the under side of the block, but is sufficiently far below the block to afford space for the heads or flanges of the cartridge-shells between it and the block. The upper side of the base-piece is provided with recesses 40 *c*, which occupy positions opposite the recesses *a* in the block A. These recesses *c* prevent any contact of the cartridge-caps or primings with the base-piece.

D designates a board, (see Fig. 2,) which 45 rests upon the top of the block A and fits within a box-like projection, A', which extends above the sides and one end of the block. The side portions of the projection A' form guides for the board D and guards to prevent powder 50 from being scattered and wasted. In this board are recesses *d*. When this board D is

drawn outward, its recesses *d* are out of line with the recesses *a* of the board A; but when the board is pushed backward they are in line with said recesses *d*. The board D is of such 55 thickness that its recesses *d* will hold the proper quantity of powder to charge the cartridge-shells. The board is first pulled outward. Then a quantity of powder is thrown upon it, and the scraper E is passed over the top to remove all the surplus. The board is then shifted backward, and the powder is delivered into the cartridge-shells. Wads are then inserted in the cartridge-shells from above with 60 any suitable instrument. The end portion of 65 the projection A', in which the board D fits, forms a stop for limiting the inward movement of said board. When the board is pushed inward against the stop, its recesses *d* are in line with the recesses *a* in the block A. The 70 lengths of the board D and block A beyond their recesses *d* *a* are such that when the end of the board is coincident with the end of the block the recesses *d* will be out of line with the recesses *a* of the block. The ends of the 75 block and board D therefore form a gage for regulating the outward movement of said board. A board, F, (see Fig. 3,) is then placed over the board D, or is put on the block A in the place of the board D. It has recesses *e*, 80 and is of such thickness that they will contain the proper amount of shot to charge the cartridge-shells. The board F is pulled outward, so that its recesses will be out of line with the recesses *a* of the block A. Shot are then poured 85 over the board and the surplus removed with the scraper. The board is then shifted backward, so as to bring its recesses into line with the recesses in the block A, whereupon the shot are delivered into the cartridge-shells. 90 Wads are then put in, and the charging of the shells is completed. The base-piece is now swung back, and the cartridges are taken out from the bottom of the block A.

What I claim as my invention, and desire to 95 secure by Letters Patent, is—

1. In an apparatus for filling cartridge-shells, the combination of a block for holding the cartridge-shells, and a board or like device having a number of recesses for holding charges 100 of powder or shot, the said block being provided at the top with projecting guides, be-

tween which the said board may be moved to bring its recesses into or out of line with the shells in the block, and which form guards to prevent the scattering of powder, substantially as specified.

2. In an apparatus for filling cartridge-shells, the combination of the block A, provided with recesses *a* and surmounted by a box-like projection, A', and the board D, provided with recesses *d* and adapted to slide in said box-like projection A', the end portion of said projection

forming a stop to arrest the board when its recesses *d* are in line with the recesses *a* in said block, and the lengths of said block and board beyond their forward recesses being such that when their ends coincide the recesses *d* will be out of line with the recesses *a*, substantially as specified. 15
